[57] **CLAIM**

The ornamental design for a disk cartridge, as shown and described.

DESCRIPTION

FIG. 1 is a perspective view of the disk cartridge;

FIG. 2 is a front elevational view of the disk cartridge;

FIG. 3 is a rear elevational view of the disk cartridge;

FIG. 4 is a top plan view of the disk cartridge;

FIG. 5 is a bottom plan view of the disk cartridge;

FIG. 6 is a left side elevational view of the disk cartridge;

FIG. 7 is a right side elevational view of the disk cartridge;

FIG. 8 is a perspective view of the disk cartridge with the front doors in the open position;

FIG. 9 is a perspective view of another embodiment of the disk cartridge;

FIG. 10 is a front elevational view of the embodiment of FIG. 9;

FIG. 11 is a rear elevational view of the embodiment of FIG. 9; and,

FIG. 12 is a perspective view of the disk cartridge with the front doors in the open position.

The undisclosed views of the second embodiment are identical in appearance to those of the first embodiment.
